US0D1093783S

(12) **United States Design Patent** (10) **Patent No.:** **US D1,093,783 S**
(45) **Date of Patent:** **** Sep. 16, 2025**

(54) **VACUUM CLEANER**

(71) Applicant: **SUZHOU AZA CLEAN ELECTRIC TECHNOLOGY CO., LTD.**, Suzhou (CN)

(72) Inventor: **Fujian Liu**, Suzhou (CN)

(73) Assignee: **SUZHOU AZA CLEAN ELECTRIC TECHNOLOGY CO., LTD.**, Suzhou (CN)

(**) Term: **15 Years**

(21) Appl. No.: **29/939,914**

(22) Filed: **Apr. 30, 2024**

(30) **Foreign Application Priority Data**

Feb. 8, 2024 (CN) 202430083639.5

(57) **CLAIM**

The ornamental design for a vacuum cleaner as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;
FIG. 10 is an enlarged view of portion 10 shown in FIG. 1;
and,

FIG. 11 is an enlarged view of portion 11 shown in FIG. 1.
The dash-dash broken lines in the drawings depict portions of the vacuum cleaner that form no part of the claimed design. The dot-dash broken lines represent boundaries of the enlarged portions and form no part of the claimed design.

1 Claim, 11 Drawing Sheets
